UNITED STATES PATENT OFFICE

MARGARET MACLEAN, OF SAN FRANCISCO, CALIFORNIA

GARMENT FASTENER

Application filed August 22, 1927. Serial No. 214,675.

This invention relates to new and useful improvements in fastening means employed for connecting and dependably supporting one under garment with respect to another.

5 The primary object of this invention is the provision of improved fastening means intended to be employed for connecting one under garment, such as a petticoat, bloomers, etc., to a corset, a corselette, or a girdle, so that the first mentioned garment will be dependent entirely upon the second mentioned garment for its support and the first mentioned garment will be held in its proper position, namely, held against twisting about 10 the body of the wearer.

15 A further object of the invention is to provide and locate improved fastening means for the aforementioned types of garments which will reduce materially the bulk of 20 ladies' wearing apparel in the region of the waistline and hips.

25 A still further object of the invention is to provide improved fastening means which will be of suitable strength and rigidity and yet will not produce any unsightly bumps or bulges.

30 Other objects and advantages of the invention will be apparent during the course of the following description.

35 In the accompanying drawings forming a part of this specification, and in which like numerals are employed to designate like parts throughout the same,

40 Fig. 1 is a side elevational view of two under garments connected by the improved fastening means and in the manner embodying this invention,

45 Fig. 2 shows in detail one element of the improved fastening means, and

50 Fig. 3 shows in detail the second element of the said fastening means.

55 In the drawings, wherein for the purpose of illustration is shown a preferred embodiment of this invention, the numeral 5 designates in its entirety an under garment, such as a corset, a corselette, or a girdle which may be of any desired style or size; a second under garment, designated in its entirety by the 60 reference character 6, is properly associated

with the garment 5 and may be a petticoat, underskirt, a pair of bloomers, etc.

Secured to the lower edge portion of the garment 5, at suitably spaced intervals, are the medallions 7 which are made of any suitable material, such as silk, satin, etc., and which are of any desired shape or size just so they are of a flat characteristic. These medallions are shown in detail in Fig. 2 and will be specifically referred to with respect thereto. The main body portion 7^a of each medallion, as stated above, may be of any desired shape or size and is intended to be directly sewed or stitched to the garment 5. This body portion preferably has depending therefrom a tongue portion 7^b. Secured to this tongue portion is a relatively flat hook 8, which may be formed of any desired material that has the requisite strength. It is believed that sheet metal will probably be 70 the most suitable material for this hook.

75 It will be noted that the medallion, being made of fabric, is flexible and will bend or flex with the garment 5. The hook 8 is of such a reduced size that it will not produce any unsightly bulge and will not catch in any garment overlying the same. It is to be understood that these combined medallions and hooks may be sold or attached to the types of garments designated generally by 80 the character 5 or they may be sold to purchasers so that they may be attached to such garments then in use.

85 The under garment 6, shown in Fig. 1, is illustrated as having suitably attached to its upper edge, as by stitching, a band 9 which has projecting upwardly therefrom a continuous line of eyes or loops 10. These loops may be made of metal, cord, or the like, and may be secured to the band in any desired 90 manner.

95 It will be understood that the specially designed garment 6, which acts as either a petticoat, a pair of bloomers, or the like, may be attached to the lower edge of the garment 5 so that the latter will entirely support the garment 6 and will hold the latter against twisting about the body of the wearer. The plurality of eyes or loops 10 will permit the garment 6 to be shifted or slightly 100

adjusted circumferentially with respect to the garment 5 whereby any desired adjustment may be made by the wearer.

The garment 6 is specially designed so as to be of a proper length to permit of its attachment to the lower edge of the garment 5 and yet not depend below the normal height of the lower edge of the ordinary garment for which it is a substitute.

10 It is to be understood that while the medallions with their hooks have been illustrated as being attached to the corset, etc., 5, and the loops or eyelets 10 attached to the band 9, I do not desire to limit myself to this 15 exact arrangement for the said loops or eyes 10 might be secured to the corset 5 while the hooks and their medallions are secured to the garment 6. It also might be noted that the hooks 8 might be secured to the band 9 while 20 the loops or eyes 10 might depend from the medallions 7.

It is to be understood that the forms of this invention herewith shown and described are to be taken as preferred examples of the 25 same, and that various changes in the shape, size, and arrangement of parts may be resorted to without departing from the spirit of the invention or the scope of the subjoined claim.

30 Having thus described the invention, I claim:

The combination with two under garments, one of which is of the corset type and extends below the waistline of the wearer, of a plurality of fabric medallions each including a looped body portion sewed to the edge of one 35 of said garments and having a narrow depending tongue left free of stitching, a flat metallic hook secured to each medallion at the lower portion of the looped body to overlie its respective tongue, a band fastened to the edge of the other of said garments, and a plurality of relatively small, closely positioned loops secured to the top edge of the 40 band, whereby the edges of said garments may be detachably and adjustably connected by the engagement of loops on the hooks.

45 In testimony whereof I affix my signature.

MARGARET MACLEAN.
